UNITED STATES PATENT OFFICE.

JOSEPH FROEHLICH, OF NEW YORK, N. Y., ASSIGNOR TO FERDINAND L. SCHMIDT,
OF NEW YORK, N. Y.

ENVELOP AND SIMILAR MACHINE.

1,006,645.

Specification of Letters Patent. Patented Oct. 24, 1911.

Application filed July 26, 1909. Serial No. 509,522.

To all whom it may concern:

Be it known that I, JOSEPH FROEHLICH, a citizen of the United States, residing at the borough of Brooklyn, Kings county, city and State of New York, have invented certain new and useful Improvements in Envelop and Similar Machines, of which the following is a specification.

My invention is an improvement of the discharging, ejecting or pushing mechanism usually employed in the folding box of an envelop machine and consists of continually revolving discharge hooks permitting a greatly increased speed of the mechanism used in the process of transferring the envelop from the folding bed to the drying chain, over the reciprocating discharge hooks in use at the present time.

Referring to the drawings Figure 1 is a longitudinal sectional view taken on the center line of an envelop machine and showing the entire mechanism in a position ready to discharge the completely folded envelop. Fig. 2 is a plan view of same looking downward from the line 2-2 in Fig. 1. Fig. 3 is a cross section taken on the line 3-3 of Fig. 1. Figs. 4, 5 and 6 are sectional views similar to Fig. 1 but showing the different positions of the mechanism.

10 In detail 1 is the plunger shown in its highest position, 2 is a creasing box, 3 is the stationary foundation or folding bed.

4 and 5 are the back and front folders respectively.

15 7 represents the finished envelop.

8 and 9 are stationary guard plates.

10 are the links of an endless chain running over sprocket shaft 11 and is for the purpose of receiving the envelop and carrying it away.

12 are the discharge hooks mounted on a continually revolving shaft 13 driven by means of the sprockets 14 and 16, and chain 15 from the shaft 17.

19 The shaft 13 is supported by the bearings 19. The sprocket shaft 11 is supported by bearings 18 and has an intermittent motion presenting the open space 20 ready to receive each envelop.

20 6 are two side folders.

The folders 4, 5 and 6 are mounted on the table 21 which also supports the folding bed 3.

When the plunger 1 has depressed the envelop blank through the creasing box 2 and attained the position as shown in Fig. 6 the folders 4, 5 and 6 are in their extreme vertical position. The plunger now ascends to its highest position, permitting the folders 4, 5 and 6 to turn downward and inward as shown in Fig. 4. The folders 4 and 6 now assume the position shown in Figs. 1 and 3, the front folder 5 raises up high enough so that its lower side is somewhat above the top side of the folding bed 3. The discharge or pushing hooks 12 moving through the slot or opening 23 of the plate 21 and slots 22 of the back folder 4 now raise up the envelop 7 to the position as shown in Fig. 5 the front end being guided underneath the front folder 5 and deflected in a downward direction by the guide plate 8. The further movement of the discharge or pushing hooks 12 now pushes the envelop completely off the folding bed. It drops by gravity through the opening in the plate 21 between the guide plates 8 and 9 into the opening 20 of the chain or drier 10 which now carries it away and presents a new opening ready to receive another envelop.

80 What I claim as my invention and desire to secure by Letters Patent is:

1. In an envelop machine, the combination, of a folding bed, a plate having an opening in suitable proximity to the folding bed and one or more continuously revolving discharge hooks for pushing the envelop from the folding bed into said opening.

2. In an envelop machine, the combination of a folding bed, a plate having an opening in suitable proximity to the folding bed, one or more continuously revolving discharge hooks for pushing the envelop from the folding bed into said opening and guides forming a channel through which the envelop is to pass.

3. In an envelop machine, the combination of a folding bed, a plate having an opening in suitable proximity to the folding bed, a drier and one or more continuously revolv-

ing discharge hooks for pushing the envelop from the folding bed through said opening into the drier.

4. In an envelop machine, the combination 5 of a folding bed, a plate having an opening in suitable proximity to the folding bed, a drier, one or more continuously revolving discharge hooks for pushing the envelop

from the folding bed through said opening into the drier and means whereby a channel 10 is formed for the passage of the envelop from the folding bed to the drier.

JOSEPH FROEHLICH.
